J. B. HADAWAY

CUSHION HEEL

Filed Dec. 15, 1922.

INVENTOR
John B. Hadaway.

UNITED STATES PATENT OFFICE.

JOHN B. HADAWAY, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

CUSHION HEEL.

Application filed December 15, 1922. Serial No. 607,077.

This invention relates to cushion heels and has for its object the improvement of such heels with respect to economy, ease and security of attachment, improved fitting qualities and durability.

Cushion heels are usually made of rubber or some composition having the characteristics of rubber, such materials being comparatively soft and resilient. It is the usual practice to attach such heels by nails to a heel base upon the heel seat end of the outer sole of a shoe or, if the entire heel is made of rubber or like material, it is nailed directly to the outer sole. Cement is commonly used to aid in securing a firm attachment and a close fit between the relatively soft rubber and the harder material to which it is attached.

The greatest difficulty in effecting a tight joint and a secure attachment between the rubber heel and the base exists at the breast corners of the heel, and the ordinary cushion heel also has the drawback that, when the shoe is presented to the heel trimming machine to trim the base to the contour of the rubber section, the comparatively soft rubber, which serves as a guide for the top lift guard of the trimming cutter, frequently yields sufficiently to permit the cutter to cut too deeply into the heel base, with the result that an excessive amount of scouring is required to produce a smooth, continuous surface around the edge of the heel and the intended shape of the heel is more or less departed from, usually to the detriment of its appearance.

According to the present invention novel stiffening or supporting elements are embedded in the region of the breast corners of the heel and are so arranged as to draw and hold the breast corners tightly against the base and to support the material of the cushion heel against yielding inwardly to any material extent under the pressure of the trimming cutter guard against its edge. By a novel combination of such stiffening members with a heel having a dished attaching face, the edges, and particularly the breast corners, of the heel are held down so tightly that there is no necessity for the use of cement and a large item of expense in attaching the heel is thus eliminated. In the illustrated embodiment of the invention the stiffening members consist of plates of comparatively hard material such, for example,

as spring steel, which are unconnected, substantially separated and arranged longitudinally of the heel. The body portions of the illustrated stiffening or reinforcing members lie approximately parallel to the side edges 60 of the heel while angularly disposed projections extend outwardly into the breast corners from the nearest nailing locations.

Preferably, one or more of the heel attaching nails are driven through suitable apertures in each stiffening member, which thus takes the place of one or more of the usual washers. In the heel herein illustrated a nail receiving slot is provided near one end of the stiffening member and a nail receiving hole 70 near its other end. When the hole is disposed in alinement with the slot, as shown, adequate provision is made for irregular spacing between the washer pins in the rubber heel mold and one size of stiffening member 75 may even be used for a plurality of sizes of heels without sacrificing its proper location in the heel. The slot and hole, as shown, are located at opposite sides of the center of gravity of the stiffening member, with the 80 result that the latter remains secure in its proper position upon the pins in the heel mold while the rubber compound is being pressed into position and vulcanized.

Inasmuch as the stiffening member extends 85 quite close to the edge of the heel near the breast corner, sufficient support is provided for the heel material to prevent it from yielding inwardly to any great extent during the trimming operation and yet, by reason of the comparatively small size and isolation of the supporting elements with respect to each other, they are free to move with the adjacent material of the heel during the shrinkage of the heel, which always occurs as an 90 incident to its vulcanization, thereby preserving their proper locations in the heel with respect to the nailing locations which are usually designated on the tread face of the latter. Furthermore the stiffening elements or members, when tensioned by the attaching nails press the adjacent edges of the heel so tightly against the base that, with a heel of the proper shape, the use of cement 95 may be dispensed with entirely.

Other features and advantages of the invention will become apparent from reading the following detailed description of one embodiment thereof in connection with the accompanying drawings, in which—

Fig. 1 is a plan view of a heel embodying the invention, a portion of the heel being broken away to reveal its internal construction;

5 Fig. 2 is a vertical section on the line 2, 2 of Fig. 1;

Fig. 3 is a perspective view of the heel attached to a shoe; and

10 Fig. 4 is a perspective view of one of the breast corner stiffening and supporting members.

Referring now to the drawings, 10 indicates a cushion heel section which may be made of rubber or like material. As herein 15 shown the heel 10 is substantially uniform in thickness throughout its area, the central portion being approximately flat and the marginal portion being curved somewhat toward the inner, or attaching, face of the 20 heel. The "dish" or concavity of the inner face of the heel is preferably sufficient to cause its edges to fit and hug tightly to the heel base when it is pressed and held flat thereon.

25 The nailing locations are designated in any suitable or convenient manner, as for example, by forming approximately conical depressions 12 at suitable places in the tread face of the heel. Co-axial with the depressions 12 are holes 14 which extend into the body of the heel to the nail head engaging members therein. As herein shown certain 30 of these nail head engaging members consist of the conventional rubber heel washers 16, 35 but the breast corner nail holes and the next adjacent holes along the side edges of the heel are not provided with such washers.

40 In the forward portion of the heel and arranged approximately parallel to its side edges are stiffening and supporting elements 45 or members 18 which are located approximately in the plane of the washers 16 and in the region of the breast corner and next adjacent nail holes.

45 Each of the members 18 comprises an elongated body portion and a tapered projection 20 extending angularly therefrom into one of the breast corners of the heel. The stiffening member 18 may be made of 50 spring steel or similar material and has near one end an elongated slot 22 the width of which is sufficient to permit the passage of the shank of a heel nail therethrough. Near the other end of the member 18 is a hole 24, 55 disposed in alinement with the slot and having a diameter approximately equal to the width of the slot. The purpose and importance of the hole and slot combination will be appreciated by those skilled in the 60 art, it being well known that the washer supporting pins in rubber heel molds frequently vary more or less in spacing either by reason of inaccurate initial location or from being more or less bent, as often happens. By providing in the member 18 one

hole and one slot the said member can be easily placed upon the corresponding two pins in the heel mold and will remain immovable thereon, regardless of variations or inaccuracy in the spacing of said pins, since 70 the hole locates one end of the stiffening member definitely with respect to one of the pins preventing the member from both longitudinal and transverse movement and the slot accommodates any variation in the 75 spacing between the pins but prevents its respective end of the stiffening member from moving transversely. This result cannot be attained with two round holes since, in order to prevent the stiffening member from shifting its position laterally the holes must fit the pins snugly and in this event it would be impossible to place the member upon the pins when the spacing of the latter was not exactly correct. The present invention offers 80 the further advantage that the same stiffening and supporting member 18 can, in some instances, be used in two or more different sizes of heels where the difference in spacing of the nails is not sufficient to exceed 85 the limits of the slot 22.

The center of gravity of the member 18 is located between the center of the hole 24 and the slot 22 to the end that the member 18 shall be properly balanced when it is 90 placed upon the pins of the heel mold and shall remain securely in position while the rubber composition is being inserted and pressed into the mold. An aperture 26 may be formed in the member 18 between the hole 95 24 and the slot 22 to permit the rubber to vulcanize together through it and add to the security with which the member is held in the heel. By reason of the tapered shape 100 and angular arrangement of the projection 20 with respect to the body portion of the member 18 the projection extends well out into the marginal portion of the heel between the line of the outer edge of the body 105 portion of the member and the edge of the heel, thus affording a maximum amount of 110 support for the yielding rubber at and near the breast corners of the heel where such support is most needed.

115 By disposing the members 18, as above described, a maximum amount of separation between them is secured. This is a matter of great importance in that it permits the natural shrinkage of the rubber to take place practically without restraint and the nail holes in the rubber, therefore, do not tend to get out of alinement with the nail receiving openings in the stiffening members. This is entirely true in a direction 120 transverse of the heel, in which direction the stiffening members are free to come and go independently of each other with the surrounding portions of the heel. By reason of the additional anchorage in the rubber, afforded by the angularly disposed projection 125 130

20, the forward end of the member 18 is secured especially well in the rubber and any tendency toward relative displacement of the holes in the rubber with respect to the holes in the stiffening member will be most likely 5 in the stiffening member will be most likely to manifest itself at the rear end of the latter. This possibility, however, is adequately provided for by the slot 22. It will, therefore, be seen that no difficulty will be 10 encountered in respect to nails which are inserted in the openings 14 passing through the holes 24 and slots 22 with certainty and accuracy.

In Fig. 3, 28 indicates the heel end of a 15 shoe, 30 being the outer sole and 32 being the base section of the heel. 34 indicates the heads of the nails which attach the cushion heel 10 to the base 32 and the shoe. It will, of course, be understood that each 20 of the washers 16 has a similar nail driven through it and each of the members 18 has two nails driven through it.

This application is a continuation, in so far as there is common subject-matter, of an 25 application of the present inventor, Serial No. 550,165, filed April 6, 1922.

Having described the invention, what is claimed as new and desired to be secured by Letters Patent is:—

30 1. A cushion heel having a pair of narrow unconnected stiffening members arranged lengthwise of the heel close to its side edges, each of said stiffening members having a heel material supporting end projecting into a breast corner of the heel at an angle to the body portion of said member and being devoid of any projections extending toward the longitudinal, median line of the heel.

40 2. A cushion heel having a pair of narrow widely separated stiffening members the body portions of which lie approximately parallel to the side edges of the heel, each of said members having a projection shorter than the body portion and extending angularly therefrom into a breast corner of the heel and being devoid of any projections extending toward the longitudinal, median line of the heel.

50 3. An elongated stiffening and supporting element for cushion heels having a nail receiving slot near one of its extremities and a nail receiving hole, substantially in aline-

ment with the slot, near its other extremity, whereby said element may be supported upon 55 differently spaced pins in a rubber heel mold without affecting its angular relation to the mold.

4. An elongated stiffening and supporting element for cushion heels having a body 60 portion containing a nail receiving slot near one end and a nail receiving hole, substantially in alinement with the slot, near its other end, and a projection at the last mentioned end disposed at an angle to a 65 line joining the hole and the slot.

5. An elongated stiffening element for cushion heels having a nail receiving slot near one end, a nail receiving hole near its other end, said hole being in alinement with 70 the slot, and an aperture of substantial size between the hole and the slot.

6. An elongated stiffening and supporting element for cushion heels, having a nail receiving slot near one of its extremities 75 and a nail receiving hole, in alinement with the slot, near its other extremity, the center of gravity of said element being between the hole and the slot.

7. A cushion heel having, in its breast corners only, separate and independent stiffening members arranged lengthwise of the heel and near its side edges only. 80

8. A cushion heel having on its tread face designated nailing locations, at certain of which are provided nail head engaging washers and at another of which is provided a stiffening member of larger area than one of the washers. 85

9. A cushion heel having on its tread face 90 designated nailing locations, at certain of which are provided nail head engaging washers and at others of which are provided stiffening members larger in area than the washers and differing in shape therefrom. 95

10. A cushion heel containing a plurality of separate and independent nail head engaging washers and a plurality of separate and independent breast corner supporting 100 members of a shape different from that of the washers.

In testimony whereof I have signed my name to this specification.

JOHN B. HADAWAY.
